UNITED STATES PATENT OFFICE

168,575

MAGNETIC THERMOMETER

Richard Kux, Detroit, Mich.

Application September 17, 1952, Serial No. 21,504

Term of patent 7 years

(Cl. D52—7)

To all whom it may concern:

Be it known that I, Richard Kux, a citizen of the United States, residing at Detroit, in the county of Wayne and State of Michigan, have invented a new, original, and ornamental Design for a Magnetic Thermometer, of which the following is a specification, reference being had to the accompanying drawing, in which:

Figure 1 is a front elevational view of a magnetic thermometer, showing my new design.

Figure 2 is a rear elevational view thereof; and Figure 3 is a section on line 3—3 of Fig. 1.

I claim:

The ornamental design for a magnetic thermometer, as shown.

RICHARD KUX.
